UNITED STATES PATENT OFFICE.

BURT A. PETERSON, OF ROCKFORD, ILLINOIS, ASSIGNOR, BY MESNE ASSIGNMENTS, TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

WARP-DRAWING MACHINE.

1,191,112.

Specification of Letters Patent. Patented July 11, 1916.

Application filed March 9, 1908. Serial No. 419,830.

To all whom it may concern:

Be it known that I, BURT A. PETERSON, a citizen of the United States, residing at Rockford, in the county of Winnebago and 5 State of Illinois, have invented certain new and useful Improvements in Warp-Drawing Machines, of which the following is a specification.

This invention relates to a drawing-in machine for placing the threads of a warp through the eyes of heddles, and for distributing the threaded heddles.

One of the objects of the invention is to provide means whereby heddles may be fed 15 from a magazine into suitable heddle frames to be subsequently used in a loom.

Another object of the invention is to provide means whereby the heddles may be threaded—*i. e.*, warp threads passed there-through—after they are fed from the magazine and before they are fed into the heddle frames.

Another object of the invention is to provide means whereby heddles may be distributed to a plurality of supports or heddle frames.

Another object of the invention is to improve, generally upon the art of drawing warps through metal heddles.

30 One form of my invention is illustrated in the accompanying drawings, in which—

Figure 1 is a side view of a warp drawing-in machine, constructed in accordance with my invention. Fig. 2 is a top plan view of 35 the mechanism shown in Fig. 1. Fig. 3 is an enlarged sectional view on the line 3—3 of Fig. 1, showing the switch and some of its associated mechanism for distributing the heddles to the heddle receptacles. Fig. 4 is 40 a transverse sectional view through the heddle guide bars, a heddle being shown in position. Fig. 5 is a front elevational view of the machine. Fig. 6 is an enlarged detail perspective view of one of the escapement members. Fig. 7 is a plan view of a portion 45 of a guide bar, the switch, one of the locator fingers and one of the pusher fingers, one locator finger being represented in position to hold a heddle for the passage of a drawing-in element therethrough. Fig. 8 is a 50 view of the same parts shown in Fig. 7, the locator finger in this view being shown as having moved away from the heddle and the pusher finger having pushed the heddles into the guide slot in the switch. And Fig. 55 9 is a fragmental view of a heddle capable of being acted upon by the mechanism illustrated herein.

The particular embodiment herein shown of the invention is especially adapted for 60 use with loom-harness frames such as are used to support metallic heddles in the loom. Such a loom harness frame may be placed upon the machine herein shown in such position that the heddles will gravitate therefrom 65 to an escapement, the heddles being released singly and successively by the escapement for movement to one or more loom-harness frames, the warp threads being drawn 70 through the heddles while the latter are in transit from one loom-harness frame to another. In Fig. 1 is shown a portion of a loom-harness frame or magazine M, said frame being provided with grooves M' to contain 75 the opposite ends of the respective heddles.

By reference to the figures in the drawings, it will be observed that the mechanism may be conveniently supported in a frame comprising a base 1, an upstanding post 2, and a laterally projecting arm 3, said arm 80 being near the upper end of the post 2. The arm 3 is shown as supporting the heddle guide bars 4 and 5 provided with T-slots 4^a and 5^a, respectively, which are adapted to align with the grooves M' of a loom-harness 85 frame placed upon the supports 4^b and 5^b, so that heddles may pass from the loom-harness frame to the guide bars 4 and 5. Supported at or adjacent to the receiving 90 ends of the guide bars 4 and 5 is a magazine M from which the heddles may be supplied into the guide bars. This magazine may be a heddle-frame which has previously been used in a loom. The portions of the bars 4 and 5 above the escapement to be hereinafter 95 described may also be considered a magazine. The guide bar 5 is provided with a horizontal extension 5^b, while the bar 4 is curved on the arc of a circle to form an arcuate guide for the lower ends of the heddles. 100 The arc is struck from a point at the juncture of the guide 5 and the extension 5^b.

The guide bar 4 and the guide 5 terminate in the same vertical plane, as will be apparent by reference to Fig. 1.

Adjacent to the lower or discharge end of the respective bars are oscillatory switches 6 and 7. The one designated 6 is provided with a T-groove 6^a which alines with the groove 4^a in the bar 4, and the groove 6^a is adapted to aline with either of a plurality of T-grooves 8 in the block 9 carried by the bracket 10 on the forward end of the base 1. Mechanism is provided for swinging the switch into registering alinement with any one of the grooves 8 (there being two shown in Fig. 3) and the mechanism is so arranged that, irrespective of which groove 8 is in alinement with the groove 6^a in the switch 6 the groove 6^a will always be in alinement with the groove 4^a. This is due to the fact that the pivotal center of the switch 6 is approximately at the discharge end of the groove 4^a. The switch 6 is supported on a pinion 11 carried by a bearing 12 in the bracket 10 and the pinion 11 is driven by a toothed segment 13 on the arm 14 of the vertical rock shaft 15. This rock shaft is supported in bearings 16 and 17 on the base 1 and the arm 3 respectively. The rock shaft 15 is provided with a crank arm 16^a which engages the groove 18^a of the cam 18, carried by the rotatory shaft 19, said shaft 19 being mounted in bearings 20 and 21 in the post 2 and the bracket 10, respectively. The switch and its cooperating mechanism, just described, is for the heddle guide bar 4. A similar mechanism is provided for the guide bar 5, the switch 7 being substantially of the same construction as the switch 6, except that it is inverted with respect to the switch 6; i. e., it has its guide groove 7^a on its under side instead of on the upper side, as has the switch 6. The switch 7 is swingingly supported on the shaft 22, carried in the bearing 23 on the arm 3, and on the end of the shaft 22 is a pinion 24 with which meshes the teeth of the segment 25, carried by the arm 26 and supported by the rock shaft 15 from which it receives a swinging motion similar to the arm 14 and in unison therewith. Mechanism is provided for regulating the feed of the heddles as they pass from the magazine into the guide bars and this mechanism is so arranged that only one heddle will be in position at any one time to receive a warp thread.

The mechanism for governing the feed of the respective heddles is clearly illustrated in Figs. 1, 2, and 5 to 8. The entire mechanism is shown as being driven from the shaft 19 and, by reference to Fig. 1, it will be observed that a cam 27 is provided on the shaft 19 and this cam 27 has a peripheral cam groove 28 to receive the crank arm 29 of the rock shaft 30, the shaft 30 being

mounted in the bearings 31 and 32. In the bearing 33 on the arm 3 is a rock shaft 34 whose upper end is connected to the shaft 30 so as to move in unison therewith. The shaft 30 is provided with a terminal arm 35 and the shaft 34 is provided with a terminal arm 36, said arms 35 and 36 being connected by a link 37 (see Figs. 1 and 2). Rigid on the shaft 30 is an escapement 38 located in approximately the same plane and coöperative with an escapement 39 on the shaft 34. A detail perspective view of one of these escapements is shown in Fig. 6, and the escapements are illustrated in plan view in Fig. 2.

By reference to Fig. 6 it will be seen that the escapement shown represents the one designated 38 and it comprises a U-shape bracket having diverging arms 40 and 41 one of which is longer than the other. The longer arm 41 is provided with an escapement plate 42 having a separating point 43, said plate being located in a plane above the plane of the plate 44 carried by the arm 40.

As has been previously explained, one object of the invention is to aline the heddle so that its eye will be in position to receive a drawing-in element. In order to insure the proper position of the heddle, it is desirable that its feeding movement be arrested during the time that the drawing-in element is passed through its eye. Adjacent to the lower ends of the guide bars 4 and 5 are what I term pusher and locator fingers. These are arranged in pairs, so as to act upon a heddle near its respective ends and thus feed it uniformly through the upper and lower switches. The locator fingers are carried by the arms 45 and 46 rigid on the shaft 30, (Fig. 1), each finger (see Figs. 7 and 8) comprising a slotted body portion 47, the heddle-engaging slot 48 of which is relatively narrow and of about sufficient width to receive the round shank of a heddle 50. Both guide bars 4 and 5 are slightly curved in a horizontal plane near their discharge ends, as seen in Fig. 3, to face the heddle eye 51 for the reception of the drawing-in element. The curves are such that the flattened portion 49 of the heddles will at the proper point, present the eye at right angles to the path of movement of the drawing-in element. The entrance to the slot 48 is flaring, in that it is provided with a relatively large entrance portion as shown at 52, the edge 53 assisting to guide the heddle into the slot 48. The pusher fingers 54 are carried by the arms 55 and 56 (Fig. 5) fixed on the shaft 30 and are in practically the same horizontal plane as their respective locator fingers 47. The inner edges 57 of the pusher fingers 54 constitute guides to assist in directing the heddles into the entrance 52 of the slots 48 and the outer cam edges 58 of the fingers 54 are capable of directing the heddles

100

120
125
130

through the grooves 6^a and 7^a in the switches 6 and 7 and into the block 9 for the lower switch, or the block 9^a for the upper switch. Upon the bracket 10 is a shoulder 10^a (Figs. 1, 3 and 5) for supporting one end of each of two loom-harness frames M or other heddle-receiving elements, the opposite ends of said receiving elements being supported in any suitable way. At the ends of the blocks 9 and 9^a are positioning tongues 59 and 60 adapted to enter recesses in the adjacent ends of the heddle-receiving elements. The grooves M' of the loom-harness frames M are adapted to aline with the grooves 8 in the block 9 and the grooves 8^a in the block 9^a.

The drawing-in element herein shown consists of a needle 64 having a hook 65. The needle 64 is shown as being carried by an arm 66 swingingly supported on the shaft 67 which is provided with a crank arm 68 engaging the cam groove 69 in the cam 18 so that by rotation of the shaft 19, either by the crank 70 or by mechanical power, the needle 64 will be caused to pass through a heddle eye to place a warp thread therethrough.

The operation of the machine herein shown will be briefly described as follows: The heddles, as, for example, those designated 50, may be placed in the magazine M the heddle-receiving grooves of said magazine being in alinement with the slots 4^a and 5^a of the guide bars 4 and 5. The heddle-frames 61 and 61^a which are to contain the heddles after the drawing-in operation are horizontally mounted at the right of the machine in Fig. 1 with their slots in alinement with the grooves 62 and 63 in the blocks 9 and 9^a. The tongues 59 and 60 will hold the receiving elements 61 and 61^a in place so that the grooves will aline with those in the blocks 9 and 9^a. The heddles may be assumed to be resting upon the escapement plates 44. Upon imparting motion to the shaft 19, the cam 27 will impart a rocking motion to the shaft 30 and thus move the escapement arms 40 and 41 causing the points 43 of the plates 42 to enter between the lowermost heddle and the one just above it and as the plates continue to move, the lowermost heddle will drop off the plates 44 and down the grooves in the bars 4 and 5. Upon the reverse movement of the oscillating shaft the heddles drop off the plates 42 and again rest upon the plates 44. As the released heddle falls from the plates 44 the end in the bar 5 strikes upon the bottom of the groove 5^a and causes the other end to swing in the arc of a circle until the heddle passes the detent spring 71 bridging the groove 4^a and hangs in a vertical position against the edges 57 of the pusher fingers 54 and in the path of the moving locator fingers 47. The locator

fingers 47 then move from the right to the left, as shown in Fig. 7, so that the heddle shall lie in the slots 48 and be thereby held in position for the threading. In this position the heddle lies in the horizontally curved portions of the grooves 4^a 5^a (Fig. 3) so that the eye will be faced with respect to the needle 64 and the movement of the parts are so timed that the heddles will be held by the fingers 47 in proper position until the hook of the needle 64 passes through an eye and recedes therefrom. During the action of the needle a thread will be passed through the heddle eye, the thread being taken from a warp which has been fed to the needle in any suitable manner.

It will be observed that the cam 27 is a two-step cam; *i.e.*, four movements, constituting two complete oscillations, will be imparted to the shaft 30 for every complete revolution of the shaft 19 and the operation of the locator fingers just described will be accomplished by one movement of the shaft 30. Upon the next movement of the shaft 30, the locator finger 47 will move away from the heddle, whose eye has just been threaded, and the pusher fingers 54 as shown in Fig. 8 will advance so that the heddle will be guided along by the cam edges 58 of the fingers 54 through the slots of the switches 6 and 7 and into the blocks 9 and 9^a. During the movement of the needle, the switches 6 and 7 are being actuated so as to present the discharge ends of their grooves 6^a and 7^a to either one or the other of the grooves 8 and 8^a, so that a heddle is fed into first the forward and then the rear groove in both blocks 9 and 9^a. Of course, it is obvious that the switches may be operated to present heddles to any number of receiving elements within the limits of the machine. In order to cause the switches to present heddles to the desired number of receiving elements, it will only be necessary to change the steps of the cam 18. As succeeding heddles are pushed into the blocks 9 and 9^a, the heddles already in these blocks will be crowded into the frames 61 and 61^a.

I would have it understood that the invention is not limited to the mechanisms and arrangement of parts herein shown, but that various modifications may be made within the scope of the appended claims.

I claim as my invention:

1. In a warp-drawing machine, in combination, heddle-guiding means; a member movable transversely of said guide means to locate the heddle for the threading operation, said member having a heddle-locating slot therein to receive a heddle situated in said guide means, and means for threading the located heddle.

2. In a warp-drawing machine, in combination, heddle-guiding means, a member

movable transversely of said guide means, said member having a heddle-receiving slot therein to hold a heddle against movement in said guide means, said slot having a flaring entrance portion to locate the heddle, and means for threading the located and held heddle.

3. In a warp-drawing machine, in combination, heddle-guiding means; a member 10 movable transversely of said guide means for holding a heddle against movement in said guide means; means for threading the held heddle; and a member movable transversely of said guide means for moving the 15 threaded heddle in said guide means, said members being arranged for synchronous movement in the same direction.

4. In a warp-drawing machine, in combination, heddle-guiding means; a rock shaft; 20 two arms fixed on said rock shaft; a member mounted on one of said arms for holding a heddle against movement in said guiding means; means for threading the held heddle; a member on the other arm for moving 25 the threaded heddle in said guide means; and means for rocking said shaft to move said members transversely of said guide means.

5. In a warp-drawing machine, in combination, heddle-guiding means; means for threading a heddle situated in said guide means; a plurality of receptacles for threaded heddles; movable heddle-guiding means for connecting the first mentioned guide 30 means with any of said receptacles; and means for moving a threaded heddle along both of said guide means into one of said 35 receptacles.

6. In a warp-drawing machine, in combination, grooved heddle-guiding means; means for threading a heddle situated in said guide means; a plurality of receptacles for threaded heddles; pivoted grooved members arranged to connect the grooves in said 40 guide means with any of said receptacles; and means for moving a threaded heddle along the grooves in said guide means and said pivoted members into said receptacles.

7. The combination of a magazine in 50 which heddles may lie side by side in a horizontal position; means for releasing heddles in the magazine to gravitating movement; an angular guide for one end of a released heddle; a guide for the other end 55 of a released heddle, the last mentioned guide being curved on the arc of a circle struck from the apex of the angle between the vertical and horizontal portions of the other guide, said curved portion terminating in a horizontal portion; escapement means for supporting heddles in said vertical portions and successively releasing them; and means for threading heddles contained in said 60 horizontal portions.

8. The combination of means for removably supporting two loom harness frames, each frame being adapted to contain the opposite ends of the respective heddles; means for controlling the movement of heddles 65 singly and successively from one frame to

the other; and means for threading the heddles.

9. The combination of means for supporting a heddle frame on its side; means for supporting a heddle frame in upright 70 position; means for moving heddles from the first mentioned frame to the other; and means for threading the heddles.

10. The combination with means for supporting a heddle frame on its side; means 75 below the first mentioned means for supporting a heddle frame in upright position; heddle-guiding means extending between said supports; means for controlling the movement of heddles along said guide 80 means; and means for threading heddles.

11. The combination, with guide means for the ends of a detached heddle, of means engaging the opposite end portions of the heddle for positioning it, and means for 85 threading the positioned heddle.

12. The combination, with guide means for the ends of a detached heddle, of means engaging the opposite end portions of the heddle for positioning it; means for thread- 90 ing the positioned heddle; and means for moving the threaded heddle along said guide means.

13. The combination, with guide means for the ends of a detached heddle, of means 95 engaging the opposite end portions of the heddle for positioning it, said guide means being shaped so as to face the heddle eye when the heddle is positioned; and means for threading the positioned and faced hed- 100 dle.

14. The combination, with slotted guides for the ends of a detached heddle, of means for positioning the heddle in said guides, the slots in the latter being curved so as to face 105 the heddle eye when the heddle is positioned, and means for threading the positioned and faced heddle.

15. The combination of two slotted heddle guides, each having a straight vertical portion, one of said guides having a horizontal portion and the other guide having a portion curved on the arc of a circle struck from the apex of the angle between the vertical and horizontal portions of the other 110 guide, said curved portion terminating in a horizontal portion; escapement means for supporting heddles in said vertical portions and successively releasing them; and means for threading heddles contained in said 120 horizontal portions.

16. The combination of means for removably supporting two loom harness frames, each frame being adapted to contain the opposite ends of the respective heddles, one above the other; means for guiding heddles in gravitating from the upper frame to the lower and means to control such movement.

17. The combination of means for remov- 130

ably supporting a loom harness frame on its side, said frame being adapted to contain the opposite ends of the respective heddles, and said side of the frame being adapted for 5 the discharge of heddles from the frame, means for removably supporting a loom harness frame in upright position; means for guiding heddles to move from the first mentioned frame to the second and means 10 to control such movement.

18. The combination of a heddle magazine, loom-harness-frame supporting means, two guides for guiding the opposite ends of heddles to pass from the magazine to a

frame removably positioned on said supporting means and means to control such movement.

19. The combination of a heddle magazine; means for removably supporting a plurality of loom harness frames; two 20 guides for guiding the opposite ends of heddles to pass from the magazine to said frames; and means for distributing the heddles to the various frames.
